Primary Examiner — Omeed Agilee(57) **CLAIM**

The ornamental design for a cartridge device, as shown and described.

DESCRIPTION

This invention was made with government support under contract number HDTRA1-17-C-0011 awarded by the Defense Threat Reduction Agency and grant number W81XWH-17-1-0694 awarded by the U.S. Army Medical Research Acquisition Activity. The government has certain rights in the invention.

FIG. 1 is a top perspective view of a cartridge device, showing our new design;
FIG. 2 is a top view thereof;
FIG. 3 is a left side view thereof;
FIG. 4 is a front view thereof;
FIG. 5 is a right side view thereof;
FIG. 6 is a rear view thereof;
FIG. 7 is a bottom view thereof;
FIG. 8 is a bottom perspective view thereof;
FIG. 9 is a top perspective view thereof in a partially folded position; and,
FIG. 10 is a bottom perspective view thereof in a partially folded position.
The broken lines depict portions of the cartridge device that form no part of the claimed design.
